(57) **CLAIM**

The ornamental design of a cage for protecting and transporting a propane tank, as shown and described.

DESCRIPTION

FIG. 1 is a perspective view of a cage for protecting and transporting a propane tank showing my new design;

FIG. 2 is an end view thereof, the opposite end view being the same;

FIG. 3 is a side view thereof, the opposite side view being the same;

FIG. 4 is a top view thereof; and,

FIG. 5 is a bottom view thereof.

The propane tank shown in phantom in FIG. 1 is for illustrative purpose only and forms no part of the claimed design.
